UNITED STATES PATENT OFFICE.

GEORGE J. ZISCH, OF NEWARK, NEW JERSEY, ASSIGNOR TO THADDEUS B. EIKER, OF ASBURY PARK, NEW JERSEY.

CARBURETER.

1,010,714.

Specification of Letters Patent.

Patented Dec. 5, 1911.

Application filed May 12, 1910, Serial No. 560,810. Renewed March 29, 1911. Serial No. 617,720.

To all whom it may concern:

Be it known that I, GEORGE J. ZISCH, a subject of Germany, and a resident of Newark, in the county of Essex and State of New Jersey, have invented certain new and useful Improvements in Carbureters, of which the following is a specification.

The invention relates to improvements in carbureters for hydrocarbon engines, and it 10 consists in the novel features, arrangement and combinations of parts hereinafter described, and particularly pointed out in the claims.

The object of my invention is to provide 15 a simple and highly efficient carbureter for automatically supplying gas of the requisite quantity and quality to the cylinder of an engine, in accordance with the work to be performed. I contemplate the use of my 20 carbureter in connection with the cylinders of automobile engines for supplying gas thereto.

The carbureter of my invention comprises, preferably, a cylindrical casing affording a 25 mixing chamber for the air and gas to be connected by suitable piping with the engine cylinder, and a receptacle for the gasoline, said receptacle surrounding the mixing-chamber and to be connected with a 30 suitable tank or source of supply for the gasoline.

The receptacle containing the gasoline will be provided with a float for closing, when the desired quantity of gasoline has 35 entered said receptacle, a valve controlling the inflow of gasoline from the tank or other source of supply to the receptacle, and said receptacle will be connected by suitable valve mechanism and a tube or pipe 40 with the mixing-chamber of the carbureter, said valve mechanism being adapted to permit of a variable discharge of the gasoline in accordance with requirements, and said tube or pipe leading from said valve mechanism into said mixing-chamber and preferably forming the pivotal axis of a suitable 45 valve of the butterfly type for controlling the passage through said chamber. The said tube or pipe is formed, within the mixing-chamber, with an outlet opening for gasoline and preferably contains a wick or body of absorbent substance which becomes 50 saturated with the gasoline and while permitting a proper discharge thereof into the mixing chamber prevents any undue quan-

60 tity of the gasoline from entering said chamber. The mixing chamber is provided at its lower portion with a suitable air inlet and an automatic check-valve therefor. The butterfly valve controlling the passage 65 through the mixing chamber and the valve mechanism controlling the variable passage of gasoline to the discharge tube or pipe connected with said valve and adapted to discharge into said chamber are connected 70 together and operate synchronously to admit proper proportions of air and gasoline to said chamber above the butterfly valve in accordance with the work required, whereby as the butterfly or air valve is 75 turned to increase the opening through the mixing chamber, the said valve mechanism will likewise open to a greater extent to supply the requisite quantity of gasoline to the increased quantity of air then passing 80 through the carbureter.

My invention results in proper combustion, high efficiency in the engine and great economy in the consumption of the gasoline, as well as accomplishing other important 85 advantages.

The invention will be fully understood from the detailed description hereinafter presented, reference being had to the accompanying drawings, in which:

Figure 1 is a central vertical section 85 through a carbureter embodying my invention, the section being on the dotted lines 1—1 of Figs. 2 and 4; Fig. 2 is a like section of the same taken at a right angle to the section of Fig. 1 and on the dotted lines 2—2 of Figs. 1 and 4; Fig. 3 is a horizontal section of the same on the dotted line 3—3 of Fig. 2; Fig. 4 is a top view of the same, the pipe leading from the carbureter to the engine cylinder being shown in horizontal section; Fig. 5 is an enlarged detached vertical section, on the dotted line 5—5 of Fig. 2, of the gasoline valve mechanism for securing a variable admission of the gasoline 90 to the transverse discharge pipe or tube in the mixing chamber; Fig. 6 is a like section through the same on the dotted line 6—6 of Fig. 2, Fig. 7 is an enlarged detached 95 view of the wick or absorbent body which I prefer to employ in the transverse gasoline discharge pipe or tube, and Fig. 8 is a sectional view corresponding with Fig. 5 but showing a modification of the gasoline valve mechanism in that the valve-disk (31) 100

110

115

120

125

130

is presented in Fig. 8 as having a continuous elongated port in lieu of the series of apertures (32) shown in Fig. 5.

In the drawings, 15 designates the exterior cylindrical shell or casing of the carbureter, 16 a top plate thereon, 17 a bottom-plate applied thereto, 18 a vertical tubular section concentric with and within the said exterior casing and forming within it the mixing chamber and conduit for the air and gas, and 19 a semi-circular float within the gasolene-receptacle 20 formed between the exterior casing 15 and tubular section 18, said float preferably being in two members connected together by a plate 14 hinged to a bracket 13 and having a laterally projecting lip or lever-arm 12, as shown more clearly in Figs. 2 and 3.

The receptacle 20 may be supplied with gasolene or the like from a suitable tank, not shown, connected with a nipple 22 screwed into the top-plate 16 and having a port 23 leading to said receptacle. At the upper portion of the port 23 is a valve-seat, as shown in Fig. 2, adapted to the valve 24, whose stem 25 extends downwardly through the port 23 in position to be acted on by the lever-arm 12 of the float 19 to open said port when the float descends by the lowering of the level of gasolene in the receptacle 20 so that an additional supply of gasolene may enter said receptacle. When the level of the gasolene in the receptacle 20 lowers, the float 19 will turn downwardly and cause the lip or lever-arm 12 to move upwardly against the valve stem 25 and elevate the valve 24 from its seat to admit an additional quantity of gasolene to the receptacle 20, and then as the gasolene reaches its predetermined level in the receptacle the float riding upwardly will turn the lip or lever-arm 12 downwardly from the valve-stem 25 and permit the valve 24 to lower and close the port 23, thereby cutting off the supply of gasolene to said receptacle.

The outlet for gasolene from the receptacle 20 to the mixing chamber 18 is through a valve-mechanism (Figs. 2, 5 and 6) and the transverse pipe or tube 26 which is pivotally mounted and extends transversely across the mixing chamber and is provided with an outlet orifice 27 in said chamber, said valve-mechanism comprising a stationary disk 28 having an arcuate recess 29 open at the outer face of the disk and in communication with a port 30 opening freely through the edge of the disk into said receptacle, an intermediate disk 31 rigid on the adjacent end of the pipe or tube 26 and having a series of ports 32 of preferably gradually increasing diameter arranged on the arc of a circle and to be brought one after another into register with the arcuate recess 29, and an outer cap 33 fitted upon and secured to a laterally projecting periph-

eral flange on the disk 31 and forming between itself and said disk 31 a chamber 34 which is closed at its outer side by said cap and into which chamber the end of the pipe or tube 26 opens to receive its supply of gasolene therefrom. The chamber 34 receives its gasolene through the port 30 and recess 29 of the disk 28 and through such of the series of ports 32 of the rotary disk 31 as may at the time be in register with the said recess 29, the flow of gasolene to said chamber and thence into the discharge pipe or tube 26 being variable in quantity according to the position of the ports 32 of the disk 31 with relation to the recess 29 of the disk 28.

The disk 28 has a hub portion set into the side wall of the mixing chamber 18 and it is stationary and affords a bearing for one end of the rotary pipe or tube 26. The disk 31 is fast on the end of the pipe or tube 26 and is in face to face engagement with the disk 28, being held firmly in such engagement by means of a nut 35 on the open end of the pipe or tube 26 and a spring 36 on said pipe or tube and acting expansively between a side wall of the mixing chamber 18 and a collar 37 on the outer solid portion of the said pipe or tube. The spring 36 and collar 37 are within a chamber 38 partitioned off from the receptacle 20, and said collar carries a stop-arm 39 provided to limit the rotary movement of the pipe or tube 26, said arm at its lower end contacting with the wall of the chamber 38 when the said pipe or tube has turned to the extent intended to be permitted and arresting the same.

The tube or pipe 26 carries, within the mixing chamber 18, a disk or butterfly valve 40 which is utilized to more or less open or close the passage through said chamber, said valve, tube and the gasolene feed-control disk 31 always moving in unison and hence proportioning the respective quantities of gasolene and air that shall come together in the mixing chamber above said valve 40. The tube or pipe 26 and parts connected with it receive their motion under the manual control of the operator or driver through any suitable mechanism comprising, for illustration, a connecting rod or link 41 pivoted to a crank-arm 42 rigid on a solid projecting end 43 of the tube 26, said end 43 and tube 26 being mounted to have a rocking or angular movement to such extent as may be required for admitting the proper quantities of air and gasolene to the mixing chamber 18 and securing the proper mixture for the engine cylinder in accordance with the work to be performed. The tube 26 will preferably contain a wick 50 or similar absorbent body adapted to hold a body of the gasolene and aid in controlling the discharge from said tube into the mixing chamber.

The upper or cap-plate 16 contains a cen-

tral opening in continuation of the mixing chamber and said plate may be fastened by screws 44 to the usual pipe 45 leading to the engine cylinder.

5 The bottom-plate or cap 17 has air-inlets 46 of small size leading to an interior air-chamber 47 formed in the lower part of the casing 15, and also a large air-inlet or opening 47 leading to said chamber but normally 10 kept closed by a check-valve 48 held on its seat by a light spring 49. During the use of the carbureter the valve 48 will be automatically opened to a greater or less extent as may be required by the suction created by 15 the piston of the engine on its suction-strokes. In the chamber 47 is provided a disk 51 of wire-cloth to screen the air which may pass to the mixing chamber.

The top and bottom plates 16, 17 may be 20 removably clamped against the ends of the casing 15 by means of rods 52 whose upper ends are in the form of adjustable bifurcated members straddling lugs 53 on the top-plate and carrying eccentrics 54 to be 25 operated by handles 55 for engaging, with binding force, the upper concaved surfaces of said lugs. The lower ends of the rods 52 are confined in lugs 56 on the bottom plate 17 and are provided with heads 57 to 30 prevent their upward movement through said lugs. By releasing the eccentrics 54 the casing 15 and all its parts below the top-plate 16 may be removed from the vehicle, and this is a feature of advantage for several reasons. 35

The operation of the carbureter will be understood from the foregoing description without further extended detailed description.

40 The carbureter having been applied to position and the receptacle 20 having been supplied with gasoline, the operation of the air-valve 40 and gasoline disk-valve 31 for the admixture of the gasoline and air will be 45 under the direct control of the driver on the car through the medium of the connecting rod 41, crank-arm 42 and tube 26. The suction stroke of the piston of the engine will be depended on, in the form of my invention 50 illustrated, for opening the air-valve 48. The driver will open the valves 40, 31 to a greater or less extent as the requirements of the engine may demand. It is one 55 of the important features of the invention that by means of the valve 31 the driver may regulate the quantity of gasoline that shall escape to the mixing chamber and that at the same time he may control, by the position 60 of the valve 40, the quantity of air in said chamber to mix with the gasoline. The operation of the valve 40 in controlling the passage of air through the mixing chamber is obvious. The disk-valve 31 contains the series of apertures 32 which in effect 65 constitute an elongated narrow port and as

said disk is turned to carry more or less of the port into communication with the gasoline recess 29 of the disk 28, the quantity of gasoline which shall pass to the pipe 26 and thence escape into the mixing chamber 18 70 will vary accordingly. If only a light load is imposed on the engine only a small quantity of gasoline will be required; under a heavier load a larger quantity of the gasoline will be required, and under a maximum 75 load a still larger quantity of the gasoline will be required, and all these variable quantities of gasoline, with the proper proportionate quantities of air, may be secured by the simultaneous movement of the disk-valve 31 and air valve 40. When the disk-valve 31 is moved to carry say two of its apertures 32 into register with the recess 29 a certain quantity of gasoline may pass to 80 the pipe 26, and as more of said apertures are carried into register with said recess a larger volume of gasoline is permitted to 85 pass to the pipe 26. As the pipe 26 is turned with the opening of the valve 40 it carries its discharge opening 27 to positions for the 90 proper discharge of the gasoline therefrom. By means of my invention the driver may very readily regulate the escape of the gasoline into the mixing chamber and the passage of the mixture of gasoline and air 95 through the carbureter to the engine.

The series of apertures 32 in the disk 31 will preferably be of gradually increasing diameter, as shown in Fig. 5, although I do not regard this as a limiting feature of my 100 invention. I desire it to be understood that I do not limit my invention to the forms and details of construction hereinbefore specifically described, since these may vary considerably within the plan and spirit of my 105 invention and with individual preference or judgment. I illustrate the elongated port through the valve-disk 31 as composed of a series of apertures 32 but I do not confine my invention to the separate apertures since 110 if the partitions between the apertures were cut away, thus leaving a narrow slot, as represented at 70 in Fig. 8, my invention would be present, since said narrow slot would be an elongated port to be moved into 115 more or less register with the gasoline-recess 29.

My invention contemplates broadly a transverse gasoline discharge tube and an air-valve in the mixing chamber and coöperating means for admitting a variable supply of gasoline to said tube. 120

In the initial assembling of the parts of the carbureter my intention is that when the air-valve 40 is transversely across the mixing chamber, as shown, only one of the apertures 32 in the disk 31 will be in communication with the recess 29. As the air-valve 125 is turned with the pipe 26 to open the passage through the mixing chamber the dis- 130

charge opening 27 in said pipe will move upwardly and an increasing number of the apertures 32 will pass into register with said recess 29.

5 What I claim as my invention and desire to secure by Letters Patent, is:

1. A carbureter comprising a casing, a mixing-chamber therein for the air and gasoline or the like, a valve controlling the 10 passage of air and gas through said chamber, a rotary gasoline discharge pipe in said chamber, valve-mechanism for admitting a variable supply of gasoline to said pipe, and means for effecting the coöperative action 15 of said valve, discharge pipe and valve-mechanism; substantially as set forth.

2. A carbureter comprising a casing, a mixing-chamber therein for the air and gasoline or the like, a valve controlling the 20 passage of air and gas through said chamber, a rotary gasoline discharge pipe in said chamber, valve-mechanism for admitting a variable supply of gasoline to said pipe, and means for effecting the coöperative action 25 of said valve, discharge pipe and valve-mechanism, said pipe having an absorbent body therein; substantially as set forth.

3. A carbureter comprising a casing, a mixing-chamber therein for the air and 30 gasoline or the like, a transverse rotary gasoline discharge pipe in said chamber, a valve connected with said pipe for controlling the passage of air and gas through said chamber, valve-mechanism for admitting a 35 variable supply of gasoline to said pipe, and means for effecting the coöperative action of said pipe and valve-mechanism; substantially as set forth.

4. A carbureter comprising a casing, a 40 mixing-chamber therein for the air and gasoline or the like, a transverse rotary gasoline discharge pipe in said chamber, a valve connected with said pipe for controlling the passage of air and gas through said 45 chamber, valve-mechanism for admitting a variable supply of gasoline to said pipe, and means for effecting the coöperative action of said pipe and valve-mechanism, said pipe having an absorbent body therein; substantially 50 as set forth.

5. A carbureter comprising a casing, a mixing-chamber therein for the air and gasoline or the like, a valve controlling the passage of air and gas through said chamber, a rotary gasoline discharge pipe in said chamber, valve-mechanism for admitting a 55 variable supply of gasoline to said pipe, and means for effecting the coöperative action of said valve, discharge pipe and valve-mechanism, said valve mechanism comprising a member having a recess in its face and open at its edge to admit gasoline thereto, a second member faced against said first member and having an elongated port through it for

60 register to a greater or less extent with said 65 register to a greater or less extent with said

recess, and a cap applied to and forming a chamber between itself and said second member communicating with said pipe, one of said members being stationary and the other rotary with said pipe; substantially as 70 set forth.

6. A carbureter comprising a casing, a mixing-chamber therein for the air and gasoline or the like, a transverse rotary gasoline discharge pipe in said chamber, a 75 valve connected with said pipe for controlling the passage of air and gas through said chamber, valve-mechanism for admitting a variable supply of gasoline to said pipe, and means for effecting the coöperative action 80 of said pipe and valve-mechanism, said valve mechanism comprising a member having a recess in its face and open at its edge to admit gasoline thereto, a second member faced against said first member and having a series of ports to be brought one after another into register with said recess, and a cap applied to and forming a chamber between itself and said second member communicating with said pipe, one of said members being stationary and the other rotary 85 with said pipe; substantially as set forth.

7. A carbureter comprising a casing, a mixing-chamber therein for the air and gasoline or the like, a transverse rotary 95 gasoline discharge pipe in said chamber, a valve connected with said pipe for controlling the passage of air and gas through said chamber, valve-mechanism for admitting a variable supply of gasoline to said pipe, and 100 means for effecting the coöperative action of said pipe and valve-mechanism, said valve mechanism comprising a plate having an elongated port through it for controlling the flow of gasoline to said pipe and means closing more or less of said port as may be required to the flow through it; substantially 105 as set forth.

8. A carbureter comprising a casing, a mixing-chamber therein for the air and 110 gasoline or the like, a transverse rotary gasoline discharge pipe in said chamber, a valve connected with said pipe for controlling the passage of air and gas through said chamber, valve-mechanism for admitting a 115 variable supply of gasoline to said pipe, and means for effecting the coöperative action of said pipe and valve-mechanism, said valve mechanism comprising a plate having a series of apertures for controlling the flow of gasoline to said pipe and means closing more or less of said apertures as may be required against the flow through them; substantially 120 as set forth.

9. A carbureter comprising a casing forming within it a receptacle for gasoline or the like and a mixing chamber for air and gasoline, a float in said receptacle, a valve controlling the inlet to said receptacle and operable by said float, a transverse rotary gaso- 125 130

lene discharge pipe in said chamber, a valve connected with said pipe for controlling the passage of air and gas, valve mechanism for admitting a variable supply of gasoline to said pipe, means for effecting the coöperative action of said pipe, air-valve and valve-mechanism, and an automatic air inlet valve at the bottom of said casing; substantially as set forth.

10 10. A carbureter comprising a casing forming within it a receptacle for gasoline or the like and a mixing chamber for air and gasoline, a float in said receptacle, a valve controlling the inlet to said receptacle and operable by said float, a transverse rotary gasoline discharge pipe in said chamber, a valve connected with said pipe for controlling the passage of air and gas, valve mechanism for admitting a variable supply

15 of gasoline to said pipe, means for effecting the coöperative action of said pipe, air-valve and valve-mechanism, and an automatic air inlet valve at the bottom of said casing, said

casing having removable top and bottom caps in the upper one of which is located the 25 gasoline inlet to said receptacle and the valve therefor, while said automatic air inlet valve is carried by the lower cap; substantially as set forth.

11. A carbureter comprising a casing, a 30 mixing-chamber therein for the air and gasoline or the like, a transverse rotary gasoline discharge pipe in said chamber, a valve connected with said pipe for controlling the passage of air and gas through said 35 chamber, and means for supplying gasoline to said pipe, said pipe having an absorbent body therein; substantially as set forth.

Signed at New York city, in the county of New York and State of New York, this 10th 40 day of May, A. D. 1910.

GEORGE J. ZISCH.
